UNITED STATES PATENT OFFICE

NICHOLAS L. GULLIFORD, OF PEABODY, MASSACHUSETTS; ARCHIBALD T. GULLIFORD, ADMINISTRATOR OF SAID NICHOLAS L. GULLIFORD, DECEASED, ASSIGNOR TO GULLIFORD WOOD HEEL COMPANY, A FIRM COMPOSED OF ARCHIBALD T. GULLIFORD, AND PEARCE H. GULLIFORD, BOTH OF LYNN, MASSACHUSETTS

MACHINE FOR FORMING HEEL BLOCKS

Application filed March 15, 1927. Serial No. 175,526.

This invention aims to provide a safe and efficient machine for making heel blocks, and in the accompanying drawings I have shown merely for illustrative purposes one complete embodiment of the invention, wherein

Fig. 1 is a plan view of the machine;

Fig. 2 is a section taken on the line 2—2 of Fig. 1;

Fig. 3 is a section taken on the line 3—3 10 of Fig. 6;

Fig. 4 is a perspective view of a strip from which the heel blocks are made;

Fig. 5 is a perspective view of a heel block; and

Fig. 6 is a plan view similar to Fig. 1, showing automatic feeding devices both for the work carrier and for feeding the strips to the saw.

In the drawings I have illustrated a machine for forming heel blanks or blocks such for example, as that illustrated in Fig. 5, comprising a flat top surface 1 and a flat bottom surface 2, herein parallel with the surface 1, a front concaved face 3 and a rear 25 convexed face 4. The concaved face 3 of the block is slightly inclined downwardly and forwardly and substantially coincides both in curvature and inclination with the breast of the finished heel. By producing

a heel block having a substantially finished 30 surface all subsequent operations necessary to complete the heel will be more easily and accurately performed with a considerable saving of material, because little surplus 35 material will be necessary to allow for variations in the block or in the positioning thereof.

It has been found most convenient to produce the concaved face of the block by means 40 of a cylindrical saw 6 having teeth 8 at one of its ends, the diameter of said saw being small enough to produce the desired curvature for heels.

The blocks shown in Fig. 5 are desirably 45 formed from a strip of suitable material such as that shown at 10, Fig. 4, and this strip is fed to the saw 6 and sections of the desired length successively severed from said strip to form the completed heel block of Fig. 5.

50 The strip 10 when ready for the sawing ma-

chine embodying this invention is generally, although not essentially, squared off at each end and of a length sufficient to produce a selected number of blocks.

As both ends of the strip 10 are flat the first cut from the strip will be for the purpose of forming a concaved face 3, following which a second cut in all respects like the first cut will be made at the proper distance from said first cut by feeding the strip 10 into the machine with the end thereof projecting the required distance beyond the plane of the cutting edge of the saw and with said strip disposed at the desired angle with respect to the axis of said saw to produce the desired inclination for the face of the heel breast. To this end I provide, as shown most clearly in Fig. 1, a guide 12 pivotally mounted at 14 upon a work-carrier 16, said guide being adjustable in a horizontal plane about the pivot 14 and adapted to be secured in different angular positions, herein by a screw 18 extending through a segmental slot 20 in the guide 12 and engaging the work carrier 16. The face 21 of the member 12 serves as a 55 guide for the top surface 1 of the strip 10 and a ledge 22 secured to said face 21 supports the strip with its median axis in the plane of the axis of the saw 6. It is however to be understood that the strip guiding edge 23 of said ledge may be moved up or down to vary the relation of the median axis of the strip 10 with respect to the axis of the saw by supplementing a ledge 22 of a different width.

Having properly positioned the strip 10 with respect to the saw, said strip is then moved bodily in a direction parallel with the axis of the saw which at this time is being rotated in any appropriate manner, as for example by belt 24 and pulley 25, and the protruding end thereof severed. This cut of the saw produces a convex rear surface 4 on the severed block and a complementary concaved front face 3 at the forward end of the remaining strip which is the end from which the next heel block is to be formed.

Each successive cut of the saw through the strip 10, herein from the top face 1 to the bottom face 2, produces complementary front 95

and rear faces for adjacent blocks, the curve for the front face corresponding to the curvature required for the breast of the finished heel. The curve of the rear surface of each 5 block roughly approximates the curve desired for the back of a finished heel, so that little material will have to be removed by the heel turning operations and at the same time a surface will be provided which materially 10 facilitates the placing of the block against the turning cutters for the final turning thereof.

To facilitate the severing of the block sections from the strip 10 the work carrier 16 15 is mounted to slide upon a suitable table 26 arranged substantially parallel with the axis of the saw 6, movement being imparted to said work carrier 16 by any suitable means and at the proper times to sever the protruding 20 end from the strip 10. In Fig. 1 of the drawings manual means are shown for moving the work carrier to and from the saw 6, said means including a handle 26' pivoted at 27 to an upright 28 on said work carrier. 25 A pin 29 slidably arranged in said upright is arranged to engage the strip 10 and when pressure is applied by the handle 26 upon said pin the near end 30 thereof will engage the strip 10 and firmly hold the same against 30 the surface 21 of the guide 12 during the sawing operations. A spring 32 is arranged to act against the pin 29 to withdraw the same from engagement with the strip 10 when pressure is removed from the handle 26, thus leaving the strip 10 free to be advanced the length 35 of another heel block.

In order to make the blocks severed from the strip 10 of uniform length I provide a 40 stop 34 which may be supported in any appropriate manner to be engaged by the concaved end face 3 of the strip 10 when the latter is advanced along the guide 12.

Where cylindrical saws are employed to 45 cut strips into small sections great difficulty has been experienced by the severed section of the strip being carried around by the saw hurled thereby a considerable distance, often breaking windows and sometimes causing injury to those standing in the path of the hurled piece. To prevent such an occurrence the present machine includes a guard having a portion 35 arranged beneath the strip 10 and a second part 36 between the saw and the strip and adjustably secured by bolt 50 to the upright 28. The part 36 of the 55 guard is approximately the same shape but slightly smaller in diameter than the interior of the saw so that when the work carrier is moved forward with the work said guard is moved forward with the work said guard will pass into the saw a distance approximating the depth of the strip 10. Upon the severing of the end of the strip said end will drop 60 against the portion 35 of the guard and be prevented thereby from revolving with the saw while still within the latter. The part 65

being substantially the size of the interior of the saw will not permit the severed block to move farther into the saw but will eject it from the saw when the work carrier is retracted. The part 35 of the guard is made narrow so as not to interfere with the dropping of the block into a suitable container after the block has been ejected from the saw.

The guard 36 being near the end of the strip 10 provides a convenient support for the stop pin 34 which latter is shouldered and set into a transverse slot 37 in said guard and clamped in position thereagainst by a nut 38. The slot 37 permits said pin to be adjusted transversely of the guard and saw to vary the length of the piece to be severed from the strip. As an additional safeguard against the hurling of the severed block I provide a second guard member 39 above the protruding portion of said strip and the gauge 34, said second guard being secured in vertically adjustable relation, against the forward face of the upright member 28 of the carrier by means of a screw 34' passing through a slot 34" in said guard and into the upright member 28.

In order to save material the initial cut upon the strip 10 is made just as close to the squared end as possible, said strip being advanced only far enough beyond the cutting edge 8 of the saw to permit this to be accomplished. This movement of the strip being irregular, it is desirable that it be performed by hand and Fig. 1 shows the machine equipped not only to advance the strip by hand but also to effect the clamping of the work and the moving of the work carrier by hand as well.

It is however desirable at times that the feeding and cutting operations be entirely automatic and to this end I have shown in Fig. 6 means for feeding the strip 10 lengthwise, said means including a trough shaped guide 35' having a pair of feed rollers 40, 42 rotatively arranged upon opposite sides thereof with their peripheries protruding slightly within the side members 43 and 44 of said guide. The feed rollers 40 and 42 are respectively secured to rotate with shafts 46 and 48. The feed roller 40 is arranged to rotate with a spur gear 50 meshing with a spur gear 52 arranged on the shaft 48 to rotate with the feed roller 42. A ratchet 54 is secured to rotate with one of said feed rollers, herein the feed roller 40, and is intermittently driven by a pawl 56 carried by an arm 58 pivoted on the shaft 46. Appropriate movement is imparted to the pawl 56 and its arms 58, by a lever 60 pivoted at 62 upon an outstanding arm 64 on the guide member 35'. A link 66 connects one end of the lever 60 with the arm 58, the latter connection being an adjustable one whereby the throw of said pawl 56 may be varied. To the opposite end of the lever 60 an extension 68 is yieldably

pivoted at 70, a spring 71 being arranged to encircle the pivot 70 and having its opposite ends secured respectively to the arm 60 and the extension 68 to normally maintain a lug 5 72 on said extension 68 in contact with a stop 73 on the arm 60. By means of this yielding connection the operating means for the arm 60 may be set to rock said arm a greater amount than will normally be required 10 but when the strip 10 strikes the stop 34 the spring 71 will yield and so permit the extension 68 to continue while the remaining parts including the feed rollers 40 and 42 remain stationary. The invention however is 15 not limited to the particular means shown.

Any appropriate means may be provided to rock the lever 60 at the proper time to effect through the feed rollers 40 and 42 the feeding of the strip 10 toward the stop 20 34, but herein I have provided for this purpose a worm gear 74 secured to a shaft 75 journaled to rotate in suitable bearings in the bed or guide member 26 of the machine. The teeth 76 of the worm gear 74 preferably engage 25 a worm 77 secured to the arbor 78 of the saw 6, which latter rotates in suitable bearings 79 on the frame 80 of the machine. An abutment 81 carried by the rotary member 74 is so positioned that at the proper time in 30 the operation of the machine it will engage the extension 68 and rock the lever 60 and through its various connections effect a predetermined rotation of the feed rollers 40 and 42. A spring 82 acting upon one end of the 35 lever 60 and secured to a portion of the guide 35 retracts the lever after the pin 81 has been withdrawn therefrom. An adjustable stop screw 83 is herein shown merely as illustrative of a means for limiting the retracting 40 movement of said lever so that the throw of the pawls 56 may be varied when it is desired to provide additional variations in the feed of the strip 10.

Cooperating with the pin 81 is a cam 45 84 secured to rotate with the shaft 75. A cam follower 85 carried herein by a reciprocating slide 86 connected at one end to the work carrier 16 is engaged by said cam 84 to impart a predetermined movement to the 50 work carrier to feed the strip 10 to the saw, but after the block is severed from said strip said carrier is returned to its normally retracted position against a stop 87, herein by a spring 88.

To provide the required friction upon the 55 strip 10 in the guide 35' I provide spring pressed rollers 89 at least along one side of the strip 10 to yieldingly press the same against one side of the guide 35'. It is also 60 desirable that one of the feed rollers be mounted to yield relatively to the other, and to this end the feed roller 42 is carried by a sliding block 90 slidably mounted in suitable guides 91 in portions of the guide member 35'. A spring 92 normally urges said

block toward the other drive roller 40 thus maintaining said roller in cooperative feeding relation with the driving roller 40. An adjusting screw 93 is provided for varying the tension of the spring 92.

It will be noted that substantially all of the parts which constitute means for feeding the strip longitudinally of the guide member 12 are carried by said guide member, therefore any adjustment of said guide member to vary the angular relation of the strip to the saw will not effect the operation of the feeding means for the reason that the pin 81 carried by the gear 74 is placed so as to provide ample throw for the lever 60 regardless of the position of the extension 68. The yielding connection between the extension 68 and the arm 60 permits said extension 68 to yield after the strip 10 has been moved sufficiently to engage the stop 34.

The relation between the pin 81 and the cam 84 is preferably such that the feeding of the strip 10 longitudinally of its guide 35' takes place only when the work carrier 16 is stationary so that there will be no interference between the several moving parts.

The pawl 56 for operating the feed roller 40 is maintained yieldingly in contact with the ratchet 54 by a spring 94 but should it be desired to render the automatic feeding devices for the strip inoperative said pawl may be thrown back to a position where said spring 94 will hold it retracted from the ratchet teeth.

Manual feeding of the strip 10 along the 100 guide 35' may readily be accomplished merely by rocking the lever 60 by hand as it is at all times free to be moved in a direction away from the abutment 81. And should it be desirable or necessary to render the lever 105 60 inoperative the stop screw 83 may be set up far enough to prevent the extension 68 from being engaged by said abutment 81.

There may also be occasions when it is 110 desirable to render the work carrier inoperative and to this end the cam slide 86 is detachably connected with said carrier by means of a screw 95 which has an end 96 for engaging a recess 97 in the slide 86 when the screw is turned in as far as it will go. With 115 the screw 95 turned out and its end disengaged from the slide the latter will be free to slide idly in the boss 98 on said carrier.

Although I have disclosed in detail one 120 full and complete embodiment of my invention, it is to be understood that the invention is not limited thereto.

Claims:

1. A machine for making heel blocks comprising, in combination, a horizontally disposed cylindrical saw, a work carrier, means to create relative movement between said work carrier and said saw in a direction axially of said saw, means for guiding the work across the cutting edge of said saw, work 125

clamping means and guard means independent of said work clamping means for preventing the hurling of the severed end of the work by said saw.

5. 2. A machine for making heel blocks comprising, in combination, a horizontally disposed cylindrical saw, a work carrier, means to create relative movement between said work carrier and said saw in a direction axially of said saw, means for guiding the work across the cutting edge of said saw at an angle to the axis of said saw, a stop for determining the length to be severed from the work and guard means interposed between the work and saw to prevent the severed end of the work from dropping into the horizontal saw and being thrown by said saw.
  - 10.
  - 15.

In testimony whereof, I have signed my name to this specification.

20 NICHOLAS L. GULLIFORD.
